UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

GEARING.

948,697.

Specification of Letters Patent. Patented Feb. 8, 1910.

Application filed April 20, 1909. Serial No. 491,102.

To all whom it may concern:

Be it known that I, BENGT M. W. HANSON, a citizen of the United States, residing at Hartford, in the county of Hartford and 5 State of Connecticut, have invented certain new and useful Improvements in Gearing, of which the following is a specification.

This invention relates to gearing and gearing comprising my invention is susceptible of advantageous use in many different connections especially in conjunction with a grinding machine as hereinafter particularly described and as shown in the accompanying drawings.

15 In the drawings accompanying and forming part of the present specification I illustrate in detail one form of embodiment of the invention which to enable those skilled in the art to practice the invention will be 20 set forth in detail in the following description while the novelty of the invention will be included in the claims succeeding said description.

Referring to said drawings, Figure 1 is a 25 front elevation of a grinding machine involving driving mechanism including my invention. Fig. 2 is a rear elevation of the same. Fig. 3 is a front elevation on a somewhat larger scale of a portion of the driving mechanism, and, Fig. 4 is a view on a similar scale of the parts shown in said Fig. 3 and as seen from the right in said latter figure.

Like characters refer to like parts throughout the several figures.

35 I shall describe somewhat briefly a grinding machine involving certain known features so that it will be more easy to understand the nature of my invention and in Figs. 1 and 2 of the drawings appears such 40 a machine which comprises a bed as 2 upon which is mounted for reciprocation longitudinally thereof the work-carriage 3 provided with a head-stock 4 and a tail stock 5 which are provided respectively with spindles 6 and 7 between which the work (not shown) is supported. The head stock 4 sustains a pulley 8 connected through the intervention of suitable mechanism with said spindle 6 so that when said pulley is rotated 45 the work will be turned. Over the pulley 8 is passed a belt 9 connected with an over-head drum 10 the length of which equals approximately the traverse of the carriage so that no matter where said carriage may 50 be it will be in driving connection with said

over-head drum. In connection with said belt is a belt-tightener such as that denoted in a general way by 11. The shaft for the drum 10 is denoted by 10' and it is sustained by the bearings or uprights 12 and 13 rising from and fastened to the bed 2. The said drum therefore while over-head is not carried by a shaft separate or independent of the machine but forms an organized part thereof and presents a very effective means 60 for driving or turning the work in that as will be hereinafter apparent the machine may be driven by an electric motor. It is therefore evident that no undue care need be exercised in placing the machine upon 70 the floor of a factory, the only requisite being the relative disposition of the driving motor and the machine itself.

I have shown as fastened to one end of the shaft 10' a cone pulley 14 connected by 75 a belt 15 with a similarly constructed but oppositely disposed pulley 16 fastened to the shaft 17 rotatively supported by suitable bearings upon the bed 2 said two cone pulleys and the belt presenting a simple means 80 for driving the said over-head drum 10 and for also changing the speed thereof.

The tool-carriage is denoted by 18 and it has a reciprocatory movement upon the upper surface of the bed 2 transversely thereof. 85 The grinding wheel is designated by 19 it being suitably supported by said tool-carriage and being operatively connected with the pulley 20 although the intermediate connections are not shown. Said pulley 20 is 90 fastened to a shaft 21 on the carriage 18 and I will hereinafter indicate how said shaft 21 is driven.

The carriage 3 is reciprocated by connections driven from the shaft 17 but I have 95 not deemed it necessary to describe or show the connections between said shaft 17 and the said work-carriage as the same are so well known. I might at this point however consider the shaft 17 a carriage reciprocating shaft and the shaft 21 a tool-turning or driving shaft. Upon one end of said tool-driving shaft 21 I have shown fastened a pulley 22 connected by a belt 22' with the pulley 23 fastened to the shaft 24 mounted 100 upon suitable bearings upon the base of the machine. Therefore when the shaft 24 is turned the tool 19 will be operated. To said shaft 24 is rigidly connected a cone pulley 25 shown as having two steps and 11.

which is adapted to be driven by a belt 26 extending from a suitable motor. It will be evident that by means of the stepped cone pulley 25 the speed of the shaft 24 may be varied and this variation in speed is what I utilize in the present instance to increase the speed of the grinding wheel 19 when the latter has its working surface worn away or reduced by reason of use. At the commencement of operation or when the grinding wheel 19 is new the belt 26 will be on the large step of the pulley 25; when said wheel is worn in the manner indicated said belt will be shifted onto the smaller step of said pulley 25 so that the speed of the said grinding wheel will be increased and although, as will hereinafter appear the carriage reciprocating shaft 17 is driven from said shaft 24, the speed of the carriage will not be changed the parts being so related that the relative velocities of the parts will remain constant.

The shaft 24 is shown as having fixed to one end thereof the pinion 27 in mesh with a spur-gear 28 both said gears being incased in a boxing 29 on the framework of the machine, and said spur gear 28 being fastened to a shaft 30 also supported by said framework. To said shaft 30 is also fastened a stepped cone pulley 31 connected by a belt 32 with a stepped pulley 33 the steps of which face oppositely to those of the pulley 31. Owing to the presence of the speed-reducing gears 27 and 28 I can drive the carriage reciprocating shaft 17 at a relatively slow speed at all times.

When the grinding wheel 19 is new the belt 26 will be on the large section of the cone pulley 25 while the belt 32 will be on the small section of the pulley 33 and the larger step of the pulley 31 by reason of which the grinding wheel 19 and carriage 3 will be operated at the proper relative speeds. Should the attendant of the machine see the necessity of speeding up said grinding wheel he will shift the belt 26 onto the smaller section of the pulley 25 and simultaneously shift the belt 32 from the smaller section of the pulley 33 and naturally at the same time from the larger step of the pulley 31 onto the smaller step thereof and although the speed of the shaft 24 is increased the speed of the shaft 17 will not be. I provide means whereby it will be impossible to shift one of said belts 26 and 32 without simultaneously shifting the other although as will hereinafter appear the belt 26 has a movement while the belt 32 is at rest, this being due simply to the fact that the belt 26 is somewhat wider than the belt 32. I should state at this point that in Figs. 2 and 3 the belts are shown as occupying their shifted positions and also that with the exception of a portion of the belt 26 in Fig. 1, all the belts are represented for

clearness, by dotted lines. The belt shifting mechanism is best shown in the enlarged Figs. 3 and 4 and the same comprises a shifter rod 34 which with its adjuncts is shown in Fig. 3 as occupying its two extreme positions by dotted and full lines, the full line position of said shifter rod being what has been considered as the shifted position thereof. Said rod is supported by suitable bearings on the framework of the machine and it has a splined connection as therewith so that said rod cannot turn as it is slid back and forth. Said rod 34 is shown as equipped with two forks 36 and 37 the fork 36 being somewhat wider than the belt 32. It is therefore clear that one of said belts (26 and 32) cannot be shifted without shifting the other although the fork 37 has some lost motion caused by the difference in width of the two belts. The fork 37 by abutting against the framework limits the movement of the rod 34 in one direction while the stop 38 limits the movement of said rod in the opposite direction. By the construction described nothing is left to chance which might be the case were the belts 26 and 32 independently or separately shifted for an attendant might shift one and neglect to shift the other.

I do not restrict myself to the exact disclosure made by the accompanying drawings and description as certain changes may be made within the scope of my invention.

In conclusion I wish to make it clear that my grinding machine comprises a tool-operating device, a carriage-reciprocating device, and mechanism for operating said devices said mechanism involving means for increasing the speed of the tool-driving device and for positively preventing an increase in speed of the carriage-reciprocating device when the speed of the tool-driving device is thus increased. In the present instance as will be obvious the speed of the carriage or table therefore remains constant and by the organization just outlined it will be impossible for the operator of the machine to change the speed of the reciprocating carriage or table.

There are certain features of a grinding machine shown and described but not claimed herein, they being made the basis of a copending application filed September 2, 1909, Serial No. 515,907.

What I claim is:

1. The combination of a shaft, a stepped cone pulley on said shaft, a second shaft, a stepped cone pulley on said second shaft, a pinion fastened to said first shaft, a spur-gear in mesh with said pinion and fastened to said second shaft, a carriage-reciprocating shaft, a stepped cone pulley on said carriage-reciprocating shaft, adapted to be belted to said second-mentioned cone pulley, a tool-operating shaft, pulleys on said first- 130

mentioned shaft and said tool-operating shaft, adapted to be belted to each other, standards rising from the framework, a drum, a shaft rotatively supported by said standards and carrying said drum, and pulleys connected with said drum shaft and carriage-reciprocating shaft, adapted to be belted to each other.

2. The combination of a shaft, a stepped cone pulley on said shaft, a second shaft, a cone pulley on said second shaft, said cone pulleys being adapted to receive separate and distinct belts, operative connections between said shafts, and mechanism for positively simultaneously shifting the belts which are adapted to run on said cone pulleys, from one step to another thereon.

3. The combination of a shaft, a stepped cone pulley on said shaft, a pinion on said shaft, a second shaft, a spur gear on said second shaft, in mesh with said pinion, a stepped cone pulley on said second shaft, said pulleys being adapted to receive separate and distinct belts, and means for causing positively simultaneously the shifting of the belts which are adapted to run on said cone pulleys, from one step to another thereon.

4. The combination of a shaft, a stepped cone pulley on said shaft, a pinion also on said shaft, a second shaft, a spur gear on said second shaft, in mesh with said pinion, a stepped cone pulley on said second shaft, said pulleys being adapted to receive separate and distinct belts, and a slidable non-rotative, belt-shifting rod having forks to receive the belts which run on said pulleys and that are adapted to simultaneously shift said belts, from one step to another of the respective cone pulleys.

5. The combination of a shaft, a stepped

cone pulley on said shaft, a second shaft, a stepped cone pulley on said second shaft, said pulleys being adapted to receive separate and distinct belts, speed-reducing gearing between said shafts, means for causing positively the simultaneous shifting of said belts from one step to another of the respective cone pulleys, a carriage-reciprocating shaft, a stepped cone pulley on said carriage-reciprocating shaft adapted to be belted to said second mentioned stepped cone pulley, a tool-operating shaft, and operative connections between said first-mentioned shaft and said tool-operating shaft.

6. The combination of a shaft, a stepped cone pulley on said shaft, a second shaft, a stepped cone pulley on said second shaft, said cone pulleys being adapted to receive separate and distinct belts, speed-reducing gearing between said shafts, means for causing positively the simultaneously shifting of the belts which run on said cone pulleys from one step to another, respectively thereof, a carriage-reciprocating shaft, a stepped cone pulley on said carriage reciprocating shaft, adapted to be belted to said second mentioned cone pulley, a tool-operating shaft, pulleys on said tool-operating shaft and said first-mentioned shaft, adapted to be belted to each other, an overhead drum, a shaft for said drum, and stepped cone pulleys on said drum shaft and carriage-reciprocating shaft, adapted to be belted to each other.

In testimony whereof I affix my signature in presence of two witnesses.
